UNITED STATES PATENT OFFICE

OTTO W. DECHAU, OF ROCHESTER, NEW YORK, ASSIGNOR TO ARTCRAFT OPTICAL CO.
INC., A CORPORATION OF NEW YORK

DESIGN FOR A BRIDGE MEMBER FOR AN OPHTHALMIC MOUNTING

Application filed March 30, 1931. Serial No. 39,303. Term of patent 7 years.

To all whom it may concern:

Be it known that I, OTTO W. DECHAU, a citizen of the United States, residing at Rochester, in the county of Monroe and State of New York, have invented a new, original, and ornamental Design for a Bridge Member for an Ophthalmic Mounting, of which the following is a specification, reference being had to the accompanying drawing, forming a part thereof.

I claim:

The ornamental design for a bridge member for an ophthalmic mounting, as shown.

OTTO W. DECHAU.
